United States Patent Office

Des. 181,066

Patented Sept. 24, 1957

181,066

ORGAN CONSOLE

William Millington, Grand Rapids, Mich., and Wilbur M. Day, Cincinnati, Ohio, assignors to The Baldwin Piano Company, Cincinnati, Ohio, a corporation of Ohio

Application December 7, 1955, Serial No. 39,190

Term of patent 14 years

(Cl. D56—2)

Fig. 1 is a perspective view of an organ console showing our new design; and,

Fig. 2 is another perspective view thereof with the fallboard being shown in a closed position.

The side opposite that shown is identical to that shown, and the back of the organ console is substantially plain. We claim:

The ornamental design for an organ console, substantially as shown and described.
